P. F. BURKE, OF WORCESTER, ASSIGNOR TO THOMAS DOOLEY, OF BOSTON, MASSACHUSETTS.

Letters Patent No. 92,259, dated July 6, 1869.

IMPROVED DIE FOR MAKING HORSESHOE-TOE-CAKES.

The Schedule referred to in these Letters Patent and making part of the same.

To all whom it may concern:

Be it known that I, P. F. BURKE, of Worcester, in the county of Worcester, and State of Massachusetts, have invented Improvements in Punching-Dies for Toe-Calks; and I do hereby declare that the following, taken in connection with the drawings which accompany and form part of this specification, is a description of my invention sufficient to enable those skilled in the art to practise it.

It has long been a common practice among mechanicians to make solid punches, to co-operate with open beds or dies, for the purpose of punching pieces of metal, of any given desired form, out of larger pieces of metal, using for the purpose one or more punches, operating at the same time; and where the surface of the metal to be punched varied from a plane, the surfaces of the punch or punches, and of the open die or dies, coming into contact with the metal, have been made the counterparts of the surfaces of the metal to be punched, so that the punchings produced had the original form of the metal, as well as the form of the punch and open die.

It follows, then, that only peculiarities of the detail of the construction and arrangement of punching-dies can now offer points of novelty, and it is in details of construction and arrangement in punching-dies that the subject of my present invention is found.

Letters Patent No. 78,581 were granted, June 2, 1868, for the invention of Thomas Dooley, for a calk or calk-blank, having a peculiar relative disposition of iron and steel, and the invention herein set forth relates to peculiarities in punching-dies adapted for punching, from rolled bars such as are described by Dooley, toe-calks or toe-calk blanks.

Figure 1 shows an end view of a bar of the material from which toe-calks are to be punched, the bars being of considerable length, part of one being shown in plan in Figure 2, the red lines in said figure showing the division-lines made by the punching-operation in forming toe-calks, the colored portion exhibiting the waste, or material to be reworked.

Figure 3 shows the punches, and their stock or carrier in end view,

Figure 4 showing the same in plan.

Figures 5 and 6 are respectively a plan and an end view of the open die or bed used in connection with the punches.

Each punch is formed from bar-steel, the piece *b*, which punches the calk steady-pin, being integral with the body *a*, of the punch, the whole of which is made by planing a bar of considerable length to the form of cross-section seen in fig. 4, marked *a b*, the punches being cut of the right length from the bar, and after being formed at one end to fit the surface of the toe-calk bar, are hardened.

The punch-carrier socket or holder is made with a

shank, *c*, to fit into a reciprocating plunger of a powerful punching-press, a head, *d*, being forged integral with the shank *c*.

In the head *d*, on opposite sides thereof, are planed seats for the reception of the punches, the ends of the punches opposite their punching-ends or faces resting solidly against square shoulders of the head *d*.

On each side of the head *d*, and resting against the bodies *a* of the punches, are located clamping-plates, *e*, through which and the head *d* and the punch-bodies *a a*, pass the clamp-bolts *f f*.

The projections *b* are preferably removed from the bodies *a* of the punches, where these enter the head *d*, and it will be seen, that if the cutting-face of either of the punches is injured, it may be ground or sharpened anew, and the new face brought into position by a filling-piece, placed between the other end of the punch and its seat or shoulder, on the head *d*.

It will be seen that the punches are not located opposite each other in their carrier, but are offset just the length of one calk, the plane of the line 1 1, of one punch, being coincident with the plane of the line 2 2 of the other punch, as shown in fig. 4.

This offset arrangement of the punches enables me to make use of two holding-bolts, in place of one only, as would be the case if the punches had an arrangement opposite each other, and said arrangement also gives a holder or carrier of much greater strength than it would have if the punches were set opposite each other. But the advantages of the offset arrangement are more marked with reference to the bed or open die *g*.

In the diagram, Figure 7, is shown an open die, similar to the die seen in fig. 5, except that the openings to receive the punches are opposite instead of offset, and it will readily be seen by practical men, that the formation illustrated in fig. 7 is too weak to withstand the force necessarily exerted in punching out toe-calks, and that the die would break at once, on the lines *z z*. But where the arrangement of the punches is offset as described, and as shown in fig. 4, and the die is made with its openings correspondingly offset, as in fig. 5, it will be seen that the die *g* has strength requisite to the performance of its functions.

On the surface of die *g* is fixed the piece *h*, which serves to guide and confine the bar from which the toe-calks are to be punched, and to strip the waste from the punches when they rise out of the die, and also to act as a stop against which the metal abuts, so that the bar can be shoved ahead under the punches, after each action thereof, exactly the length of one toe-calk.

The piece *h* projects above die *g*, like a bridge over the path of the bar from which the calks are punched, the part marked *i* allowing one rib, *j*, of the bar, to pass under it, while rib *k* of the bar abuts against the

part of the bridge marked *l*, which does not leave space enough between its lower surface and the upper surface of the die *g* to permit the passage of rib *k*. The sequence of the cutting of the punches on the bar of metal is numerically indicated in fig. 2.

If the punches were made integral with each other and with their carrier, their first cost would largely exceed the cost of the construction shown, and any injury of one of the punches would ruin the entire combination for use. But in my improved construction, if either of the punches is injured, it may be repaired, or if beyond repair, it may be replaced with but comparatively small expense.

The ease and facility with which each separate part

of my combination may be tempered, will at once be recognized by practical workers of steel.

I claim, for punching-dies for toe-calks, the offset arrangement of the punches and the openings in the die, substantially as shown and described.

Also, the non-integral structure, consisting of the carrier *c d*, separate punching-cutters *a b*, *a b*, clamping-plates *e e*, and bolts *f f*, substantially as and for the purposes specified.

Also, the bridge *h*, combined with the die *g*, and operating substantially as and for the purpose specified.
